UNITED STATES PATENT OFFICE.

FRANKLIN HARDINGE, OF CHICAGO, ILLINOIS, ASSIGNOR TO HARDINGE BROTHERS, A CORPORATION OF ILLINOIS.

FASTENER FOR CLOSURES.

1,330,184.

Specification of Letters Patent. Patented Feb. 10, 1920.

Original application filed January 28, 1915, Serial No. 4,841. Divided and this application filed April 20, 1918. Serial No. 229,694.

To all whom it may concern:

Be it known that I, FRANKLIN HARDINGE, a citizen of the United States, residing at Chicago, in the county of Cook and State 5 of Illinois, have invented a certain new and useful Improvement in Fasteners for Closures, of which the following is a full, clear, concise, and exact description, reference being had to the accompanying drawings, 10 forming a part of this specification.

This invention relates to improvements in casing closures.

The objects of the invention are:

First, to provide a new and improved 5 form of means for holding or locking a closure of a casing in its closed position, the said means being of such a character as to require manipulation before the closure can be opened, but constructed in such a manner 20 that the closure can be moved to its closed position without any separate manipulation of the locking means.

Second, to provide means of the character 25 described, which includes a thumb piece to be manually operated prior to the opening of the closure, and which is so formed and coacts with the cover in such a manner as to be moved out of the path of the cover when the latter is being closed.

30 Further objects will appear as the description progresses, reference being had to the accompanying drawings in which I have illustrated my invention in connection with the gear casing of an engine lathe.

35 Figure 1 is a perspective view of the headstock end of a lathe; and

Fig. 2 is a sectional detail view on line 2—2 of Fig. 1.

In both figures similar reference characters 40 refer to similar parts.

Referring to the drawing the reference character 5 indicates the head stock spindle of a lathe, which is driven through the cone pulley 6 and is geared through a train of 45 gears to the lead screw shaft 7. A part of this gear train is located in the casing 8, through one side of which projects a handle 9, which is used for manipulating certain change speed gearing, the details of which 50 form no part of the present invention.

Pivoted to the casing by means of the pintle 10 is a cover 11, the free edge of which is spaced from the adjacent edge of the casing. The opposed edges of the cover and casing

are provided with vertical abutments 12 55 and horizontal abutments 13, which coact to lock the handle 9 in certain adjusted positions.

While the weight of the cover 11 is sufficient to maintain it in its closed position under ordinary working conditions, in order to prevent any accidental displacement of the cover, I provide means for locking it in its closed position. This means comprises a plunger 14, which reciprocates in a bore 60 15 formed in the casing, and is prevented from rotating in the bore by means of a set screw 16, which extends into a slot 17 65 formed in the side of the plunger. The plunger 14 is urged upwardly by a spring 70 18 in the bottom of the bore 15. The upper end of the plunger is provided with a thumb piece 19, which has an outwardly and downwardly inclined cam surface, which co-acts with the lower edge of the cover 11 to push 75 the thumb piece 19 and the plunger 14 downwardly out of the path of the lower edge of the cover while the cover is being closed. When the cover has been moved to its closed position the spring 18 returns 80 the thumb piece to its uppermost position in which the inner edge thereof acts as an abutment for maintaining the cover in its closed position. To release the cover it is simply necessary to push the thumb piece 85 downwardly, whereupon the cover may be opened by means of the handle 20.

This invention is a division of my application, Serial No. 4,841 filed January 28, 1915. 90

Having described my invention, what I claim is:

1. The combination with a casing provided with an opening, of a cover for said opening having one edge pivotally mounted 95 on said casing, and means coacting with an edge of said cover opposite said pivoted edge for holding said cover in its closed position, comprising a plunger reciprocally mounted in said casing, and provided with a thumb piece for holding the cover closed, the said thumb piece having an inclined cam surface for coacting with the cover to move the thumb piece out of the path of the cover when the cover is being closed, and means for coacting with said plunger to prevent rotation of said thumb piece. 100

2. The combination with a casing pro-

vided with an opening of a cover for said opening having one edge pivotally mounted on said casing, and means coacting with an edge of said cover opposite said pivoted edge for holding said cover in its closed position, comprising a thumb piece, means for coacting with the cover to move said thumb piece out of the path of said cover when the cover is being closed, and auto-

matic means for positioning the thumb piece 10 to lock the cover when the latter is in its closed position.

In witness whereof I hereunto subscribe my name this 17th day of April, 1918.

FRANKLIN HARDINGE.
